US00D894264S

(12) **United States Design Patent** (10) **Patent No.:** **US D894,264 S**
Sarro et al. (45) **Date of Patent:** **** Aug. 25, 2020**

(54) **LABEL PRINTER FOR SYSTEM FOR
CUSTOMIZING HAIR DYE FORMULATIONS**

(71) Applicant: **Coty Inc.**, New York, NY (US)

(72) Inventors: **David Sarro**, Frankfurt am Main (DE);
Tiziana Monaco, Frankfurt am Main (DE); **Tim Whateley**, Leicester (GB);
Jonathan Ashbridge, Leicestershire (GB); **Liam Burns**, Leicester (GB)

(73) Assignee: **Coty Inc.**, New York, NY (US)

(**) Term: **15 Years**

(21) Appl. No.: **29/639,707**

(22) Filed: **Mar. 8, 2018**

(51) LOC (12) Cl. **18-99**

(57) **CLAIM**

The ornamental design for a label printer for a system for customizing hair dye formulation, as shown and described.

DESCRIPTION

FIG. 1 is a perspective view of a label printer for a system for customizing hair dye formulations;

FIG. 2 is a front elevation view thereof;

FIG. 3 is a rear elevation view thereof;

FIG. 4 is a first side elevation view thereof;

FIG. 5 is a second side elevation view thereof;

FIG. 6 is a top plan view thereof; and,

FIG. 7 is a bottom plan view thereof.

The broken lines depict portions of the label printer system for customizing hair dye formulations that form no part of the claimed design.

1 Claim, 7 Drawing Sheets
